UNITED STATES PATENT OFFICE.

IVAR F. WARME, OF SYRACUSE, NEW YORK, ASSIGNOR, BY MESNE ASSIGNMENTS,
TO CONTINENTAL CAN COMPANY, INC., A CORPORATION OF NEW YORK.

MECHANISM FOR FEEDING CAN ENDS.

1,092,613.

Specification of Letters Patent.

Patented Apr. 7, 1914.

Application filed December 17, 1910. Serial No. 597,786.

To all whom it may concern:

Be it known that I, IVAR F. WARME, a citizen of the United States, residing at Syracuse, in the county of Onondaga, State 5 of New York, have invented certain new and useful Improvements in Mechanism for Feeding Can Ends, of which the following is a description, reference being had to the accompanying drawing and to the letters 10 and figures of reference marked thereon.

My invention relates to new and useful improvements in mechanism for feeding can ends.

An object of the invention is to provide 15 means for supporting can ends in a stack, and for separating said can ends one by one from the bottom of the stack and conveying the same to the machine wherein the can end is operated upon.

20 A further object of the invention is to provide means for holding a stack of can ends and feeding the same one by one therefrom, which means may be readily adjusted for different sized can ends.

25 These and other objects will in part be obvious, and will in part be hereinafter more fully disclosed.

In the drawings which show by way of illustration one embodiment of my invention,—Figure 1 shows a double-seaming machine having my improved end feeding mechanism applied thereto; Fig. 2 is a vertical section through the can end feeding mechanism; Fig. 3 is a horizontal sectional view on the line 3—3 of Fig. 2; Fig. 4 is a plan view of the supporting and separating device; Fig. 5 is an edge view, looking in the direction of the arrow 5; Fig. 6 is an edge view, looking in the direction of the arrow 35 6; Fig. 7 is a detail showing one of the spacing devices used in adjusting the stack holder; Fig. 8 is a detail view, showing the lower end separated from the stack; and Fig. 9 is a similar view, showing the lower 40 45 end released and dropping into the conveyor, which leads to the machine.

In Fig. 1 I have shown more or less diagrammatically a double-seaming machine, which consists of a supporting base 1 on 50 which is mounted a rotating carrier 2, which rotating carrier is provided with a plurality of pairs of rotating chucks 3, adapted to engage a can body and can end and to rotate the same. On the carrier is also mounted a 55 plurality of double-seaming rolls, which engage and form the seam between the can

end and can body. The can bodies are fed from a conveyor 4 into pockets formed in the rotating support, where the can body is temporarily held until engaged by the rotating chucks. The carrier is rotated by a gear 5 from a gear 6 on the main shaft. 60

The mechanism above described forms no part of the present invention, but has been described as the desired type of machine to 65 which my can-end-feeding mechanism is to be applied, and further to aid in a clear understanding of the can-end-feeding mechanism.

Mounted on a standard rising from the 70 frame of the machine 1 is a bracket 7. Said bracket is formed with a horizontally extending portion 8, in which is formed an opening 9 slightly larger than the largest can end desired to be fed to an operating 75 machine. Rising from the supporting bracket 7 are four standards 10, 11, 12 and 13. These standards are located in recesses 10^a, 11^a, 12^a and 13^a, respectively, formed in the side wall of the opening 9 in the bracket 80

7. The standards 10, 11 and 12 are rigidly secured to the bracket by suitable screws 14. The standard 13 is secured to the bracket 7 by a bolt 15. This standard 13 may be secured directly against the bracket 7, or a 85 spacing washer 16 may be inserted between the standard and the bracket, in order to rigidly hold said standard in a position removed from the bracket, and closer to the standard 11. When the spacing washer is 90 omitted, then the standards carried by the bracket are so positioned as to form an opening or space between the same of substantially the same size as the opening 9 in the bracket. These standards are for the purpose of directing and supporting a vertical 95 column or stack of can ends laid one on the other. At the lower end of the standard 13 is a tapered lug 17, which is held thereon by a bolt 18. This tapered lug 18 extends beyond the edge of the standard 13, and the can ends at the lower end of the column or stack will rest at one side on said tapered lug. At the other side of the bracket, I have provided a rotating separator 19. Said 105 rotating separator 19 is rigidly secured to the upper end of the shaft 20^a, which is geared to the shaft 21, and said latter shaft is in turn geared to the gear 6, which rotates the carrier of the double-seaming machine. 110

As the double-seaming machine carrier rotates, the separating device will be caused

through the intermediate shaft connections to rotate in proper timing therewith. Said separating device 19 is preferably made of cast iron, and is formed with a supporting ledge 20, which extends only a portion of the way around the separating device, thus leaving a space or cut-away portion 21, which as herein shown extends through an arc of substantially 90°. This supporting ledge 20 extends beyond the inside edge of the standard 10 11, and, therefore, lies in the path of the stack of can ends, so that said can ends rest on said ledge. In order that the lower can end of the stack may be separated from the 15 remainder of the ends and released, I have provided a separating plate 22, which is preferably made of hardened steel. The upper face of the separating device is formed with a recess to receive said hardened 20 plate, which is attached in the recess by suitable screws 23. Said plate at its forward end relative to the direction of rotation, projects substantially in a radial direction, as at 24, over the supporting ledge 20. Said radially projecting edge is tapered or sharpened, so as to form a thin cutting edge, which will with certainty extend between the can ends resting one upon another, and lift the stack 25 from the lowermost end, so that the weight of the stack will be taken from said lowermost end on to the separating plate 22. The lowermost end will, therefore, pass underneath the separating plate 22, and as soon as the cut-away portion 21 in the separating device 30 passes underneath the released lower can end, then the side of the can end adjacent the separating device will drop, as indicated in Fig. 9, while the opposite edge of the can end will be held temporarily upon the tapered supporting lug 17, until said can 35 end swings around substantially to a vertical position, when said opposite edge will be released and the can end will drop. The supporting bracket 7 is provided with a tapered section 25, which tends to guide the can end and carry the same to a vertical position in the conveying slot 26, which leads to the double-seaming machine. By forming the plate 22 as a separate section, I 40 am able to make the same of hardened steel, and to quickly remove and replace the same when said plate becomes worn. Furthermore, by forming the plate 22 with a substantially radially projecting separating 45 edge, I have formed a separating edge which will positively enter in between the can ends and separate the same. The supporting plate 22 is arranged in a horizontal plane, while the supporting ledge 20 is also arranged in a horizontal plane at a slight distance below the plate 22. It will be seen, 50 therefore, that when the can ends in the stack are resting on the supporting ledge 20, they will be in a substantially horizontal position. When the separating plate enters be-

tween the lowermost end and the other ends in the stack, the stack will be carried by said plate with the ends still held in a horizontal position. This construction of separating device avoids all lateral tilting of the 70 can ends, as the separating plate enters between the ends in the stack, and, therefore, the ends will be readily released without cramping or binding, which is likely to clog the machine. 75

The separating device has an outwardly extending body portion 27, and the end thereof adjacent the space 22 is tapered as at 28. This tapered face extends upward across the space between the plate 22 and the supporting ledge 20, so that when the lowermost can end is separated from the stack, if for any reason it fails to drop when the supporting ledge passes from underneath the same, the tapered face 28 will engage said released 85 can end and force the same from the stack, so that it will drop from the feeding device.

While I have shown my device as applied to a double-seaming machine, it is obvious that said feeding device may be used in connection with machines of other types, and it is also obvious that said feeding device as set forth in the appended claims, may be used for feeding flat disks of any character, and that my invention is not limited to the 90 feeding of can ends. It is also obvious that minor changes in the details of construction and arrangement of parts may be made, without departing from the spirit of my invention. 95

Having thus described my invention, what I claim as new and desire to secure by Letters Patent, is:—

1. In a device for feeding can ends or the like, the combination of a stack holder, means for supporting the stacked ends in said holder and releasing said ends one by one, including a rotatable member having a horizontal supporting ledge, said ledge being cut away to permit the ends to drop from said member, and a separating plate located in a plane above said horizontal ledge and having a substantially radially projecting separating edge extending over said ledge. 110

2. In a device for feeding can ends or the like, the combination of a stack holder, means for supporting the stacked ends in said holder and releasing said ends one by one, including a rotatable member having a horizontal supporting ledge, said ledge being cut away to permit the ends to drop from said member, and a removable hardened steel separating plate located in a plane above said horizontal ledge and projecting over the same. 120

3. In a device for feeding can ends or the like, the combination of a stack holder, means for supporting the stacked ends in said holder and releasing said ends one by 130

one, including a rotatable member having a horizontal supporting ledge, said ledge being cut away to permit the ends to drop from said member, and a removable hardened steel 5 separating plate located in a plane above said horizontal ledge and projecting over the same, said plate having a substantially radially projecting separating edge.

4. In a device for feeding can ends or the 10 like, the combination of a bracket, standards secured to the bracket for supporting a stack, a tapered stud carried by the bracket, means whereby said stud may be adjusted toward and from the center of the stack, and a separating 15 device disposed opposite to said stud for engaging the other side of the can ends, and for releasing one can end at a time.

5. In a device for feeding can ends or the 20 like, the combination of a bracket, standards secured to said bracket, a tapered stud carried by one of said standards for supporting one side of the stack of can ends, a separating device for engaging the other side of the 25 can ends for releasing one can end at a time, and means for adjusting said standard carry-

ing said tapered stud, whereby said holder is adapted for different sized can ends.

6. In a device for feeding can ends or the like, the combination of a stack holder, means for supporting the stacked ends in said 30 holder and releasing said ends one by one, including a rotatable member having a horizontal supporting ledge, said ledge being cut away to permit the ends to drop from said member, a separating plate carried by said 35 member and located in a plane parallel with and above said ledge, said separating plate having a substantially radially projecting separating edge extending over said ledge, and said member having a tapered edge ex- 40 tending from said ledge to said separating plate for stripping the can ends from said separating member.

In testimony whereof I affix my signature, in presence of two witnesses.

IVAR F. WARME.
